MAGNETRON

Karl Fritz and Rudolf von Radinger, Berlin, Germany, assignors to Telefunken Gesellschaft für Drahtlose Telegraphie m. b. H., Berlin, Germany, a corporation of Germany

**Application April 7, 1937, Serial No. 135,372
In Germany April 30, 1936**

9 Claims. (Cl. 250—27.5)

The present invention relates to electron discharge devices of the so-called magnetron type and has for its principal object the provision of frequency determining means for such tubes comprising a shielded concentrically symmetrical oscillatory circuit. The electron discharge device is inserted in the oscillatory circuit. In a modification of the invention, means are disclosed by which the natural wave of this oscillatory circuit 10 can be gradually varied.

It is known that tuned circuits of poor radiation can be obtained by disposing a casing as part of the oscillatory circuit symmetrically around the other current carrying parts, and connecting this casing with the other parts so that the current flowing in the oscillatory circuit is uniformly distributed over the entire casing. In these oscillatory circuits no outer electrical or magnetic field can develop.

Short wave tubes are also known in which the frequency determining oscillatory circuit comprises two coaxial tubes, these tubes containing the electrodes as parts. The electrodes, or the parts acting as electrodes are situated in the center of the two cylinders. The axial length of the tube is approximately equal to one wave length. In the usual known tubes moreover, there is no way of varying the natural wave.

As compared with conventional tubes, the tube according to the invention has the advantage that its axial length is considerably shorter. The tube in the most unfavorable case, requires at maximum a length of about $\lambda/2$ as measured in the direction of the axis of the oscillatory circuit. The oscillatory circuit is to be considered essentially as a quasi-stationary circuit. Its geometrical length will in general be considerably shorter than $\lambda/2$. Due to its novel construction, the tube furthermore offers the advantage that the natural frequency of the oscillatory circuit can be varied.

The short wave tube, and more particularly the magnetron tube according to the invention, and in conjunction with a concentrically symmetrical oscillatory circuit of poor radiation, comprising two coaxial cylinders within which the discharge system is arranged, is characterized by the fact that the oscillatory circuit is completely shielded at its outer circumference except for the lead-ins for the operating voltages, and the outgoing connections for the high frequency, that the two cylinders are connected with each other at their ends as regards high frequency, that the innermost cylinder is opened approximately in the center, and that the separated surfaces

form the anodes of the discharge system. Ordinarily, the inner cylinder will be so opened that the separated surfaces are at a finite distance from each other, forming preferably parts of a cylindrical surface, the cathode being placed at the axis of the cylinder.

Preferably the separated faces are confined by parts of a cylinder surface the axis of this cylinder extending perpendicular to the axis of the oscillatory circuit.

In view of the fact that the concentrically symmetrical oscillatory circuit is closed, more especially directly closed along the outer circumference as regards high-frequency, it is possible in a simple manner to resort to measures and to provide means whereby the natural frequency of the oscillatory circuit can be varied from the outside.

The novel features which we believe to be characteristic of our invention are set forth with particularity in the appended claims, but the invention itself will best be understood by reference to the following description taken in connection with the accompanying drawings in which Figure 1 is a schematic perspective of an oscillatory circuit arrangement embodying the principle of our invention, Figure 2 is a longitudinal section of a tube and circuit schematically shown and embodying our invention, Figures 3 to 6 inclusive and Figure 10 are sections of modifications schematically shown of the tube and circuit shown in Figure 2 with tuning arrangements, Figures 7, 8a, and 8b show diagrammatically the cathode and circuit arrangements in a tube embodying our invention, Figures 9a and 9b are diagrammatic representations of means of coupling a tube and circuit made according to our invention to an output device, Figure 11 is a diagram illustrating a method of voltage application to a tube of the kind shown in Figure 10, and Figure 12 is a schematic showing of a means for varying the oscillating frequency of a tube and circuit made according to our invention.

The principal structure of the oscillatory circuit employed will now be described in reference to Figures 1 and 2.

Figure 1 shows an oscillatory circuit of poor radiation and concentrically symmetrical with respect to the axis R, such as is known in general. The inductance of this circuit is formed by the outer conductor L_o and parts of the inner conductor L_i. The capacitance is represented by two circular disks C₁ and C₂ arranged at the inner ends of the legs of the inner conductor parts L_i.

Figure 2 shows in principle a tube according

to the invention. Two cylinders L_a and L_b are electrically connected to each other and their ends closed by members S ringlike in form. The inner cylinder L_b which may be a solid cylinder, is opened up approximately at the center of the tube. The cathode K is arranged laterally to the place of separation or in the center between the separated surfaces A_1 and A_2 . In the case represented the separated surfaces form parts of a cylindrical surface whose axis extends perpendicular to the central axis of the oscillatory circuit comprising the inductances L_a , L_b and the capacitances existing between surfaces A_1 , A_2 . Magnets M outside the casing provide a magnetic field parallel to the cathode K .

In the tube shown in Figure 3, the oscillatory circuit consists of a fixed part containing the discharge system comprising cathode K , and anodes A_1 , A_2 , and the central parts L'_1 and L'_a of the coaxial cylinders, and of one or two parts L'' and L''' movable in the axial direction, and which reach in a cap-like manner over the open ends of the fixed central part and have coaxial inwardly extending tubular extensions T , T' cooperating with the inner tubular member. The actual discharge space is closed up in a gas tight manner from the outer space by a tubular envelope G , the envelope being coaxial with the tubular members L'_a and L'_1 . The ends of the envelope G are sealed to the inner tubular member L'_1 . The mechanical connection between the inner part L'_1 and the outer part L'_a for supporting these parts in spaced relationship is established by the envelope G and the insulation support O arranged for instance in a ring about the inner part. By suitable means the movable parts can be displaced in the direction of the arrows P whereby the operating wave length can be varied, or the cap like members may be threaded to engage threads on the outside of the outer tubular members.

Figure 4 shows a similar tube. It comprises only two telescoping tubular parts L'_1 , L'_a , and L'' , L''' which can be turned relative each other. The movable parts engage each other in a sleeve like manner at the circumference of the outer cylinder. These overlapping parts may be threaded at W . The tube envelope G is a tubular member coaxial with the tubular members L'_1 and L'_a and is closed at its ends, the ends being sealed to the tubular members L'_1 .

In the tubes according to Figures 5 and 6 the oscillatory circuit consists of a mechanically rigid unit. About the separated parts L_1 and L_2 of the inner cylinder but outside the discharge system, metal parts M or dielectric D are provided by means of which the resultant capacity between the separated faces can be varied, more especially increased.

Figure 5 shows a tube of the above mentioned type. The arms of the inner cylinder have arranged thereon two metal shields M having the shape of a cone surface or spherical cap, such that the openings having the largest diameter are situated opposite each other approximately above the discharge path. The metal shields terminate into hollow cylinders H which can be moved in axial direction on the arms of the inner cylinders. The rods V represent the adjusting rods for moving the movable parts and extend through and are guided along a slot in the inner cylinder. The tubular glass envelope G is sealed to the tubular members L_1 and L_2 in the same manner as shown in Figures 3 and 4.

In the tube shown in Figure 6, for the pur-

pose of varying the wave length, a cylinder D is placed over the two arms of the inner cylinder, this cylinder D being composed of adjacent cylinders having any desired diameter. In order that, especially in case of equal diameters, a variation in the capacity might be obtained, the individual partial cylinders are made of materials with different dielectric constants. In the forms of applicants' invention shown in Figures 6 and 7 the inner and outer tubular members L_a and L_b and L_1 and L_2 are closed and joined at their ends to form the envelope of the tube. The members L_a , L_b , and L_1 and L_2 are preferably tubular members which are cylindrical in cross section, the inner ends of the tubular members L_1 and L_2 being formed to provide the anode segments A_1 and A_2 .

Figures 7 and 8 show examples for suitably connecting the operating voltage sources.

In Figure 7, the plate potential U_a is applied to the outer cylinder at any desired point W' and the heating voltage is introduced at N' of the outer casing or shield casing. Since with proper assembling, no high frequency currents flow on the outer side of the casing of the oscillatory circuit, no potential differences exist between the individual points of the outer surface. Therefore, the plate potential can be applied to any desired place of the casing of the oscillatory circuit.

For the part of the heating circuit situated inside the oscillatory circuit the most accurate symmetry is of course required, otherwise undesirable compensation currents would flow across the heating lines.

Various propositions have already been made for arranging the heating line and filament coaxially to the inner cylinder of an oscillatory circuit of the mentioned type with relatively poor radiation. Figure 8a shows a suggested arrangement making use of an electromagnet M' . The two anodes representing the parts of the inner cylinder L_b are oppositely disposed longitudinally. The filament and the heating current line are arranged in the axis of the inner cylinder. In these arrangements it is very difficult to withhold high frequency currents from the filaments. High frequency compensation currents pass across the ordinarily high ohmic resistance of the filament K , which originate for instance at the anode A_1 and pass across the natural capacity C' , then across the filament K and across the second capacity C to the anode A_2 . When passing through the filament K losses occur in accordance with the ohmic resistance of the filament, which increase the damping of the oscillatory circuit.

If for any reason despite this condition it is desired to bring out the heating current lead-ins in the rotational axis of the oscillatory circuit, it is necessary to select an arrangement according to Figure 8b. According to the invention the filament K extends perpendicularly to the symmetry axis. The two lead-ins are bent into an angle and are arranged to pass in front of the front faces of the anodes, and are then brought out in the axis.

To prevent any high frequency leaks towards the outside, the heating lead-ins after leaving the discharge chamber are choked by means of chokes X , or made to undergo proper damping. At the ends of the inner cylinder L_b capacitances C are suitably placed between the heating lines and the casing of the oscillatory circuit. In this case the

high frequency losses are confined to the filaments proper.

Figures 9a and 9b show two examples for connecting radiators. The radiator S' is current coupled. The course of the current is indicated in dash lines. The radiator S'' is voltage coupled. The connection with the outer surface of the inner cylinder L_1 is established in a capacitive manner for instance by means of two capacitive surfaces 10 faces F.

Figure 10 shows a construction slightly deviating from the idea of the invention. The parts of the inner cylinder L_1 instead of being directly connected with the outer cylinder are capacitively connected with the movable parts L'' , L''' of the outer cylinder. The distances between the ends of the inner parts L_1 oscillating so to say, as dipoles having the length $\lambda/2$, and those of the movable outer parts L'' and L''' are variable. In order to obtain a definite course of the field lines, the movable parts may be provided with attachments Z.

The application of the voltage to these dipoles involves in general somewhat greater difficulties. A relatively simple solution resides in connecting the plate potential source to the voltage nodes of the inner parts L_1 and choosing the length of the line up to the outer shield casing L_2 approximately $\lambda/4 + n\lambda/2$, whereby $n=0, 1, 2, 3$ etc. as shown 30 in Figure 11.

The idea of the present invention is in no way limited to the examples of construction as described and shown in the drawings. If required, auxiliary electrodes may be inserted between the cathode and the anodes. The forms of the oscillatory circuits, and more especially the measures and means for varying the natural frequency are in their application not limited to magnetron tubes, but may also be used in tubes which are 40 operated without magnetic field.

If the tube is to be used in conjunction with a radiator, it will often be desirable to enclose the latter within an envelope. If in view of reasons in the construction, this solution is not possible, 45 the radiator can be used apart from the tube, and the energy can be supplied across a special line, or capacitively or inductively through the glass wall.

It is advisable to use non-magnetic material 50 for the outer cylinder, since at operation of the tube in a magnetron circuit, the field lines of the magnetic field must permeate the outer cylinder, in order to be permitted to act upon the discharge path situated in the interior.

The possibility of varying the operating wave 55 length (natural frequency of the oscillatory circuits) is not confined to the examples herein shown. The movable parts M or D may also be shaped differently within the oscillatory circuit, 60 and may be operated by a lever drive, and may be brought outside through springy sealing-in parts such as glass springs Q as shown in Figure 12.

While we have indicated the preferred embodiments of our invention of which we are now aware and have also indicated only one specific application for which our invention may be employed, it will be apparent that our invention is by no means limited to the exact forms illustrated or the use indicated, but that many variations may be made in the particular structure used and the purpose for which it is employed without departing from the scope of our invention as set forth 75 in the appended claims.

What we claim as new is:

1. An electron discharge device for use at high frequencies and including a pair of concentric tubular members electrically connected at their ends, the inner tubular member being mechanically separated at the middle and formed to provide a pair of oppositely disposed anode segments, a cathode positioned between said anode segments and means for providing a magnetic field parallel to said cathode and anode segments. 10

2. An electron discharge device for use at high frequencies including a pair of concentric tubular members of predetermined length electrically connected at their ends, the inner tubular member being mechanically separated at the middle and formed to provide a pair of oppositely disposed anode segments transverse to the longitudinal axis of said tubular members, a straight thermionic cathode positioned between and co-axial of said anode segments and means for providing a magnetic field parallel to said cathode and anode segments. 15

3. An electron discharge device for use at high frequencies and including a pair of concentric tubular members electrically connected at their ends by solid flat ring-like members to enclose the space between the tubular members, the inner tubular member being mechanically separated at the middle and formed to provide a pair of oppositely disposed anode segments, a cathode positioned between said anode segments and means for providing a magnetic field parallel to said cathode and anode segments. 25

4. An electron discharge device for use at high frequencies and including a pair of concentric tubular members and means for electrically connecting the tubular members at their ends and including a cup-shaped member, the inner tubular member being mechanically separated at the middle and formed to provide a pair of oppositely disposed anode segments, a cathode positioned between said anode segments and means for providing a magnetic field parallel to said cathode and anode segments, said cup-shaped member being movable longitudinally of said tubular members 40 to vary the natural frequency of oscillation of the electron discharge device. 45

5. An electron discharge device for use at high frequencies and including a pair of concentric tubular members, means for electrically connecting the tubular members at their ends and including a cup-shaped member having a coaxial tubular extension cooperating with the inner tubular member, the inner tubular member being mechanically separated at the middle and formed to provide a pair of oppositely disposed anode segments, a cathode positioned between said anode segments and means for providing a magnetic field parallel to said cathode and anode segments, said cup-shaped member being movable longitudinally of said tubular members to vary the natural frequency of oscillation of the electron discharge device. 55

6. An electron discharge device for use at high frequencies and including a pair of concentric tubular members and means for electrically connecting the tubular members at their ends and including a cup-shaped member having a coaxial tubular extension cooperating with the inner tubular member, the inner tubular member being mechanically separated at the middle and formed to provide a pair of oppositely disposed anode segments, a cathode positioned between said anode segments and means for providing a magnetic field parallel to said cathode and anode 75

- segments, said cup-shaped member being movable longitudinally of said tubular members to vary the natural frequency of oscillation of the electron discharge device, and an envelope around 5 a portion of the inner tubular member for enclosing the anode segments and cathode.
7. An electron discharge device for use at high frequencies including a pair of tubular concentric members and means for electrically connecting the tubular members at their ends comprising a pair of cup-shaped members, the inner tubular member being mechanically separated at the middle and formed to provide a pair of oppositely disposed anode segments, a cathode positioned between said anode segments, and means for providing a magnetic field parallel to said cathode and anode segments, said cup-shaped members being movable longitudinally of said tubular members to vary the natural frequency 10 of oscillation of the electron discharge device.
8. An electron discharge device for use at high frequencies, including a pair of concentric tubular members electrically connected at their ends, the inner tubular member being mechanically separated at the middle and formed to provide a pair of oppositely disposed anode segments transverse 15 of the longitudinal axis of said tubular member, a cathode positioned between said anode segments and means for providing a magnetic field parallel to said cathode and anode segments, cup-shaped members having their open ends opposed and provided with tubular extensions for slidably supporting the cup-shaped members on the inner tubular member adjacent the anode segments, and means for moving said cup-shaped members toward and from each other to vary the capacity 20 between the anode segments, and an envelope enclosing said cathode and anode segments.

segments, cup-shaped members having their open ends opposed and slidably mounted on said inner tubular member adjacent said anode segments and means for moving said cup-shaped members toward and from each other to vary the capacity 25 between the separated ends of the inner tubular member.

9. An electron discharge device for use at high frequencies and including a pair of concentric tubular members electrically connected at their ends by solid flat ring-like members to enclose the space between the tubular members, the inner tubular member being mechanically separated at the middle and formed to provide a pair of oppositely disposed anode segments transverse 30 to the longitudinal axis of said tubular member, a cathode positioned between said anode segments and means for providing a magnetic field parallel to said cathode and anode segments, cup-shaped members having their open ends opposed and provided with tubular extensions for slidably supporting the cup-shaped members on the inner tubular member adjacent the anode segments, and means for moving said cup-shaped members toward and from each other to vary the capacity 35 between the anode segments, and an envelope enclosing said cathode and anode segments.
